H. L. WOOD

BATTERY POST CLAMP

Filed April 1, 1922

INVENTOR
Harry L. Wood,
BY Parker Macklin,
ATTORNEY'S

UNITED STATES PATENT OFFICE.

HARRY L. WOOD, OF LAKWOOD, OHIO.

BATTERY-POST CLAMP.

Application filed April 1, 1922. Serial No. 548,864.

To all whom it may concern:

Be it known that I, HARRY L. Wood, a citizen of the United States, residing at Lakewood, in the county of Cuyahoga and State of Ohio, have invented a certain new and useful Improvement in Battery-Post Clamps, of which the following is a full, clear, and exact description, reference being had to the accompanying drawings.

10 This invention relates to an apparatus which is adapted for use in connection with the sealing of battery posts to jar covers, and has for one of its objects the construction of a device for enabling battery jars to be sealed in accordance with the method set forth in my copending application No. 453,927, filed March 21, 1921.

20 My invention is more particularly concerned with the provision of a portable hand actuated clamp which is well adapted for use in service stations for positioning the posts and cover in proper relation to each other and then applying pressure, whereby the posts may be built up to the finished size 25 while pressure is being applied. To this end, my invention is directed toward the construction of a clamp which is simple in construction and capable of use on all sizes of jars to be sealed.

30 The means for carrying out my invention will be fully set forth in the following description which relates to the drawings and the essential characteristics of my invention will be summarized in the claims.

35 In the drawings, Fig. 1 is a plan view of a clamp constructed in accordance with my invention; Fig. 2 is a side elevation thereof; Fig. 3 is a vertical section taken through the clamp on the line 3—3 of Fig. 1 and showing the battery jar cover in position on the platen with the clamping jaws unlocked; and Fig. 4 is a similar section showing the jaws locked to the cover and posts.

Designating the parts shown in the drawings by the use of reference characters, 10 indicates a base, 11 a standard, and 12 the platen or lower jaw of a clamp which is adapted to support a pair of battery posts and their associated grids. As indicated in Fig. 2, the platen may be provided with recessed portions 13 extending longitudinally thereof for positioning the battery posts 14 laterally to bring them into registration with the cover 21 prior to the building-up process. The upper jaw of the clamp is shown at 15 as an overhanging plate rigidly

secured to a post 16, which is vertically movable within a tubular opening 17 in the standard 11; a spring 18 being positioned at the bottom of the opening for normally holding the post 16 and its attached jaw 15, out of contact with the jar cover to be sealed.

For enabling pressure to be applied against the battery posts and cover, I provide a handle 20 which is rigidly secured to the post 16, and is so positioned thereon that the jaw 15 may be quickly brought into engagement with the battery post cover 21 by manually forcing the handle 20 downwardly and compressing the spring 18. To lock the cover between the jaws, I have shown a spindle 25 which is freely movable within the jaw 15 and which is threaded, as at 26, to engage a threaded opening 27 in the platen 12. The upper end of the spindle is 75 provided with a crank 28, having a handle 29 attached thereto, whereby the jaws may be quickly clamped to hold the posts 14 together with the removable rings 30, securely to the cover 21. 80

The method of sealing posts to a cover, as described and claimed in the above mentioned application, embodies briefly, the bringing of a ring 30 into engagement with the cover 21, and over the post 14, and then 85 while pressure is being applied, to unite the ring and post and finally build it up to the finished thickness. Accordingly, to provide a form of mold for enabling the post to be built up, and at the same time construct a 90 clamp capable of gripping all sizes of posts, I have shown the jaw 15 as having openings arranged in pairs, and of different sizes, as at 32 and 33 respectively. In addition, I have shown post building molds 34 which are positioned within the openings 33, and which are adapted to be made integral with the jaw, or to be removably held therein as desired. 95

In operating a clamp constructed according to my invention, the posts and cover to be sealed, are placed on the platen 12, and the rings 30 positioned over the post openings in the cover and beneath the openings in the jaw 15. Then the jaw 15 is brought into engagement with the rings 30 by pressing down upon the handle 20 until the jaw engages the top of the cover, whereupon the jaws are clamped by turning the crank 28, thereby drawing the spindle 25 through the opening 27. In this way, sufficient pressure 110 may be applied to hold the posts and rings to the cover, while the posts are being built

up to the finished size. The posts are built up to the required size by the addition of lead in a molten state within the post opening in the mold. Usually the exposed surface of the severed post is heated as by a blow-torch, before the molten metal is added to obtain a firm bond with the added material.

A clamp constructed according to my invention is well adapted for use in garages or service stations, because of the fact that it is light in weight, portable, capable of receiving all sizes of posts, and for holding them securely during the sealing operation.

The arrangement of the parts enables the posts, together with the associated grids, to be readily positioned on the platen, and thereafter clamped to the cover with the expenditure of slight effort, and in addition permits the sealed members to be quickly released.

Having thus described my invention, I claim:—

1. A battery post clamp comprising in combination, a pair of jaws, one of which is movable, one of said jaws being shaped to hold a pair of posts and to position them laterally for receiving a battery cover, and means for moving one of said jaws to clamp the post and cover between said jaws.

2. A battery post clamp comprising in combination, a stationary jaw and a movable jaw, the stationary jaw being shaped to receive and support a pair of posts and to position them for receiving the battery cover, and means for clamping the post and cover between said jaws.

3. A battery post clamp having in combination, a pair of jaws, one of said jaws comprising an overhanging platen formed to receive a pair of battery posts and to position them laterally for receiving a battery jar cover, and the other of said jaws comprising an overhanging member having openings in registration with the post openings of said cover, and means for clamping said posts and cover between the jaws.

4. A battery post clamp having in combination, an overhanging stationary jaw adapted to engage the under side of a battery post to position it for engagement with a battery jar cover, a movable jaw above the stationary jaw, yieldable means for normally holding the movable jaw away from the parts to be clamped, and means for clamping the jaws together after the upper jaw has been moved against the force of the yielding means, and into engagement with said parts.

5. A battery post clamp having in combination an overhanging stationary jaw shaped to receive battery posts and to position them laterally for engagement with a battery jar cover, a movable jaw above the stationary jaw, yieldable means for nor-

mally holding the movable jaw away from the parts to be clamped, and means for clamping the jaws together after the movable jaw has been moved against the force of the yielding means.

6. A battery post clamp comprising in combination, a pair of horizontal jaws, the lower jaw being shaped to support a pair of battery posts and to position them laterally for registration with a battery jar cover, the upper jaw being movable for clamping the posts and cover together, a spring for normally holding said last mentioned jaw away from the cover, and means whereby the movable jaw may be manually depressed to bring it into abutting engagement with the object to be clamped, and means for thereafter locking said object between said jaws.

7. A battery post clamp comprising in combination a base, a standard and a platen protruding laterally from the top of the standard and overhanging said base, a jaw rigidly carried by said standard and overhanging said platen, a spring for normally holding said jaw away from said platen, means whereby the post may be manually depressed against the force of the spring to bring the jaw into engagement with the object to be clamped, and other means for thereafter clamping the jaw to the object while it is held in abutting engagement therewith.

8. A battery post clamp comprising in combination a base, a hollow standard, and a platen protruding laterally from the top of the standard and overhanging said base, a spring within the standard, a post resting on said spring and slidably mounted in said standard and projecting thereabove, a jaw rigidly secured to the top of said post and overhanging said platen, means whereby the post may be manually depressed against the force of the spring to bring the jaw into engagement with the object to be clamped, and other means for thereafter clamping the jaw to the object while it is held in abutting engagement therewith.

9. A battery post clamp comprising in combination, a base, a hollow standard, and a platen projecting laterally from the standard and over the base, said platen being shaped to receive a pair of battery posts and to position them laterally for receiving a battery jar cover, a spring within the standard, a member projecting above the platen and resting on said spring, an upper clamping jaw carried by said member and having openings therein in registration with the post openings in the cover, and means carried by said jaw for engaging the platen and locking the object to be clamped therebetween.

10. A battery post clamp comprising in combination, a base, a hollow standard, and a platen projecting laterally from the stand-

ard and over the base, said platen being shaped to support a pair of battery posts and to position them laterally for receiving a battery jar cover, a spring within the 5 standard, a member projecting above the platen and resting on said spring, an upper clamping jaw carried by said member and having openings therein in registration with the post openings in the cover, a threaded 10 spindle extending downwardly from said jaw and normally out of contact with said platen, and means whereby the spindle may be moved to engage the platen and clamp the post to the cover.

15 11. A battery post clamp comprising in combination, a pair of horizontally disposed cantilever supported jaws, the lower jaw being shaped to support a pair of battery posts and to position them laterally for receiving a battery jar cover, a threaded spindle extending downwardly from the upper jaw, and terminating short of the lower jaw, a crank secured to the upper end of 20 said spindle, and means whereby the upper jaw may be manually depressed to engage the object to be clamped, and thereafter locked by bringing the threaded portion of the spindle into engagement with the lower jaw.

25 12. A battery post clamp comprising in combination a pair of horizontally disposed overhanging jaws, the lower jaw having a width sufficient for enabling a pair of battery posts to be moved longitudinally there- 30 of, and to be supported thereon in position to engage a battery jar cover, the upper jaw

having openings in registration with the post openings in said cover, a mold carried by the jaw adjacent the openings therein, and means for locking the object to be 40 clamped intermediate said jaws.

13. A battery post clamp comprising in combination a pair of superimposed cantilever supported jaws, the lower jaw having a width sufficient for supporting a pair of 45 battery posts in position to engage a battery jar cover, the upper jaw having openings in registration with the posts and a threaded spindle extending downwardly from the upper jaw intermediate the posts, 50 said spindle being adapted to pass through the vent opening in the cover and to engage the lower jaw.

14. A battery post clamp having in combination, a pair of jaws disposed one above 55 the other, the lower jaw being shaped to support a pair of battery posts and to position them laterally for receiving a battery jar cover and the upper jaw having openings therein in registration with said posts, 60 a mold extending upwardly from each of said openings an amount sufficient for enabling the post to be built up to the finished size, a threaded spindle carried by the upper jaw and adapted to extend through the 65 vent opening in the cover to engage the lower jaw and a crank secured to the spindle above the upper jaw.

In testimony whereof, I hereunto affix my signature.

HARRY L. WOOD.
